UNITED STATES PATENT OFFICE

RALPH L. SKINNER, OF DETROIT, MICHIGAN

INTERNAL-COMBUSTION ENGINE

Application filed May 19, 1930. Serial No. 453,579.

My present invention relates to several structural betterments in engines of the internal-combustion type and appliances of similar character, such as pumps, one of its leading aims being to provide an engine or the like which seals the gas pressures in its cylinders in adequate manner by very simple means, the construction being designed in such a way that the inner cylinder or sleeve, 10 employed inside of the outer cylinder, and the sliding valves, which reciprocate between such cylinders may be removed and replaced with ease and dispatch.

To the accomplishment of these and other 15 desirable objects I have devised the present, preferred embodiment of the invention in an internal-combustion engine, illustrated in the accompanying drawings, forming a part of this specification, and to which reference 20 should be had in connection with the following detailed description, like numerals having been employed to designate the same parts throughout the several views.

In this drawing:

25 Figure 1 is a central, vertical, longitudinal section through one cylinder of a multi-cylinder engine;

Figure 2 is an enlarged, detail, fragmentary section through the upper portion of the inner cylinder;

Figure 3 is a partial section showing the mounting of the lower end of the inner cylinder on an enlarged scale;

Figure 4 is a horizontal section on line 4—4 30 of Figure 1;

Figure 5 is a fragmentary, vertical section through the engine crank-shaft indicating the mounting for the inner cylinder;

Figures 6 and 7 indicate steps in the removal of one of the sliding valves;

Figure 8 is a vertical section showing one of the steps in the removal of the valves; and

Figure 9 presents a slightly modified construction and the method of taking its valves 35 out.

Referring to these drawings for a full understanding of the invention, both from structural and functional standpoints, it will be observed that the improved and novel engine includes a main or outer, preferably

water-jacketed cylinder 11, desirably, but not necessarily, cast integral with the upper section 12 of the crank-case, the ordinary, lower, readily-detachable portion or pan-shaped part of which is not shown, the cylinder having the customary fuel-inlet port 13 and the usual, opposite exhaust-port 14.

Depending from the cylinder-block or casting into the upper part of the crank-case is a pair of spaced, curved walls 15 concentric with, and forming partial extensions of, the cylinder and having threaded apertures 16 in enlargements 17 at their lower ends receiving the upper screw-threaded ends of four screws or bolts 18 having shoulders 19, at the junctions of their threaded sections with their cylindrical shanks of slightly larger diameter, bearing against the under surfaces of the parts 17.

A supporting ring 21 is slidably mounted on the four screws, the latter extending through holes 22 in the ring which is carried or supported on coiled springs 23, 23 encasing or encircling the shanks of the screws, pressing at their upper ends on the under side of the ring and bearing at their lower ends on washers 24, 24 resting on the angular heads 25 of the screws or bolts, a small gap or space being present between the top surface of the ring and the bottom faces of the walls 15, whereby to permit a limited, vertical play of the ring, which is provided for the purpose of supporting an inner cylinder or sleeve 26 having near its lower end two, narrow, external, annular shoulders 27, 28 (Figure 3) 85 resting on companion or complementary, internal edges of the carrying ring 21, such inner cylinder having snug fits in the ring above the shoulder 27 and below the shoulder 28, and having a shallow space between these 90 two, interfitting members between the shoulders.

As is shown, such cylinder may, if desired, extend down a short distance below the ring.

It will be observed that the construction is such that the cylinder may be readily slid upwardly out of its supporting-ring to de-mount it therefrom, if occasion requires.

It may be noted that the ring has a main, central body portion 29, a circular flange 31

depending therefrom, and a thinner, annular, upstanding flange 32 interposed between the members 15 and the inner cylinder 26.

A water-cooled cylinder-head 33 and its cover close the upper end of the outer cylinder with the head extending down into it in the usual way, leaving a thin or shallow, circular space between them, the under face of the head having a flat surface 34 bearing on which is the top edge of a split, expansible, resilient, sealing-ring 35 having inlet and exhaust-ports 36 and 37, respectively, in register with the corresponding ports 13 and 14 of the outer cylinder, the top edge or end of the inner cylinder pressing upwardly against the bottom face of and supporting the sealing-ring by reason of the action of the several springs 23, 23.

If desired, in order to make the top of the inner cylinder broader or wider and to allow the gas pressure in the cylinder to tend to force it upwardly, it may have a bearing ring 38 fixed thereto in any approved manner and forming a part thereof, the ring being of greater thickness than the cylinder and extending inwardly beyond its inner surface.

From the foregoing, it will be apparent that the spring-urged, upward pressure of the inner cylinder on the ported sealing-ring 30 secures a compression or gas-pressure tight relation between them and between the sealing-ring and the cylinder-head, at the same time allowing the capacity for expansion and contraction of the ring, the top and bottom faces of which are at right angles to its axis.

Two, substantially semi-circular, inlet and exhaust valves 39 and 41 are slidable between the outer cylinder on the one hand, and the inner cylinder, sealing-ring and cylinder-head on the outer hand, the inlet-valve 39 having a port 42 therethrough adapted during the vertical, reciprocatory stroke of the valve to be brought into and out of register with the corresponding ports of the outer cylinder and the sealing-ring, the exhaust-valve 41 having a port 43 similarly shifted into and out of register with the complementary ports of the cylinder and sealing-ring.

Valve 39 is reciprocated in proper-timed relation to the movements of the other parts of the mechanism by a suitably-rotated eccentric or crank-shaft 44 joined by a connecting-rod or link 45 to a wrist-pin 46 mounted in spaced lugs or ears 47 rigid with, and outstanding from, the lower portion of the valve between the margins of the adjacent supporting walls 15, which, if desired, may act as guides for the valve by their co-operation with the lugs or ears.

In similar manner, the exhaust-valve 41 is actuated by an eccentric or crank-shaft 48 and its associated connecting-rod 49.

The power-piston 51 fits and slides in the inner cylinder and its connecting-rod 52 is

operatively united with the main crank-shaft 53 of the engine in the usual way.

Thus, the sealing-ring is maintained in pressure-tight relation with the cylinder-head and the inner cylinder in similar relation with the ring by the constant, upward, pressing action of the springs 23 on such shiftable cylinder, the force exerted by such springs being augmented or increased, during the explosion gas pressure and during the compression in the cylinder by the action of such pressures on the under side of the overhanging part of the element 38 of the inner cylinder, and yet, the sealing-ring can press outwardly against the valves under its own tendency to enlarge supplemented by the gas pressure inside of it, and the valves in turn are forced outwardly against the inner surface of the outer cylinder.

In this way, the gas pressure is sealed in the cylinder against leakage or improper escape, assuring correct, efficient and economical operation of the engine.

Another important feature of the invention is the comparatively easy removal of the inner cylinder and the valves, if occasion demands.

This may be accomplished in either one of two ways.

Turning first to Figures 1, 6, 7 and 8 of the drawing, the bottom pan (not shown) of the crank-case having been demounted, the connecting-rod 52 is easily disconnected from the main crank-shaft 53 from below and then the power-piston 51 and such connecting-rod are taken out downwardly or upwardly.

Thereupon, the connecting-rods 45 and 49 of the valves are disconnected from their operating shafts 44 and 48 and from the pins 46, 46, the parts 45, 49 and 46 being easily removed downwardly from the engine.

The cylinder-head 33 and its cover and the sealing-ring 35 having been removed from the top of the outer cylinder, the companion, inner cylinder is readily pushed up from the bottom out of its supporting ring and taken out of the open top of the external cylinder.

Thereupon, the ring 21, its bolts 18, and the associated springs 23 and washers 24 are demounted and removed from below.

Then the main crank-shaft 53 is turned to bring its crank-section into horizontal position under the valve 39 which is pushed up the full distance it will go (see Figure 8), and the companion valve 41 is slid down until its upper end is lower than and thus clears the bottom end of the elevated valve 39, this descent being permitted by having the eccentric or crank shaft 48 for such second valve 41 turned to position its crank-section horizontally away from the valve, the cheeks of such crank-section being chamfered as shown in Figure 6 to allow the valve lugs to pass down by them.

This having been accomplished, the lower valve is turned 90 degrees (see Figure 8), shifted bodily sidewise, and slid out down between the cheeks of the corresponding crank-portion of the main crank-shaft.

After that, it is an easy matter to take the other valve out in similar manner.

In some engines, equipped with crank-shaft counterweights and in which the valves cannot be turned the specified 90 degrees, it is necessary to remove the valves in a somewhat different manner.

In such a case, the bottom end of one valve is cut away at its opposite, longitudinal edges at 54 (Figure 9) and the opposite, upper, lengthwise edges of the companion valve are bevelled at 55.

In this instance, the one valve cannot be slid down substantially straight sufficiently to escape or clear the companion valve, but by providing the specified recesses in the mating edges of the valves, with the one valve at its upper limit of travel, the complementary valve may be slid down in an inclined position and thus removed, the main crank-shaft being turned at the same time, if necessary, to follow the travel of the valve and allow its downward passage by it.

One of the two valves having been thus extracted, the second one may be withdrawn in comparable manner.

Attention is directed to the fact that in thus demounting the several specified parts of the engine, there is no separation of the cylinder-block from the upper portion of the crank-case, and, in fact, because this is not required, they can be cast integral, which results in distinct economic and functional advantages, and it is to be perceived, further, that none of the eccentric shafts are disturbed. If, therefore, it becomes desirable either to remove the inner cylinder or to take out the valves, this may be accomplished comparatively quickly and at relatively small expense.

Although only two embodiments of the invention have herein been set forth, it will be readily understood by those skilled in this art that the invention is susceptible of other embodiments differing in mechanical structure from those set forth, but incorporating its fundamental principles, as defined by the following claims.

I claim:—

1. In an internal-combustion engine, the combination of an outer ported cylinder, a head for said cylinder, a ported expandible sealing-ring bearing on said cylinder-head, an inner longitudinally-movable cylinder bearing on said sealing-ring, a piston slideable in said inner cylinder, a crank-shaft, a connecting-rod joining said piston and crank-shaft, means to press said inner cylinder lengthwise against said sealing-ring and to press said sealing-ring against said cylinder-head to seal the joints between said inner

cylinder, sealing-ring and cylinder-head against the escape of gas pressure from said cylinder, valve-means between and slideable lengthwise of said outer cylinder on the one hand and said inner cylinder and sealing-ring on the other hand, and means to reciprocate said valve-means.

2. In an internal-combustion engine, the combination of an outer cylinder having inlet and exhaust ports, a head for said cylinder, an expandible sealing-ring bearing on said cylinder-head and having inlet and exhaust ports in substantial register with said cylinder-ports, an inner lengthwise-movable cylinder bearing on said sealing-ring, a piston slideable in said inner cylinder, a crank-shaft, a connecting-rod joining said piston and crank-shaft, means to press said inner cylinder longitudinally against said sealing-ring and to force said sealing-ring against said cylinder-head to seal the joints between them against the escape of gas pressure in the cylinder, arcuate valves between and slideable lengthwise of said outer cylinder on the one hand and said inner cylinder and sealing-ring on the other hand, and means to reciprocate said valves.

3. In an internal-combustion engine, the combination of an outer cylinder having inlet and exhaust ports, a head for said cylinder, an expandible sealing-ring bearing on said cylinder-head and having inlet and exhaust ports in substantial register with said cylinder-ports, an inner lengthwise-movable cylinder bearing on said sealing-ring, a piston slideable in said inner cylinder, a crank-shaft, a connecting-rod joining said piston and crank-shaft, yielding means to press said inner cylinder longitudinally against said sealing-ring and to force said sealing-ring against said cylinder-head to seal the joints between them against the escape of gas pressure in the cylinder, arcuate valves between and slideable lengthwise of said outer cylinder on the one hand and said inner cylinder and sealing-ring on the other hand, and means to reciprocate said valves.

4. In an internal-combustion engine, the combination of an outer cylinder having inlet and exhaust ports, a head for said cylinder, an expandible sealing-ring bearing on said cylinder-head and having inlet and exhaust ports in substantial register with said cylinder-ports, an inner lengthwise-movable cylinder bearing on said sealing-ring, a piston slideable in said inner cylinder, a crank-shaft, a connecting-rod joining said piston and crank-shaft, yielding means acting on the lower end of said cylinder to press said inner cylinder longitudinally against said sealing-ring and to force said sealing-ring against said cylinder-head to seal the joints between them against the escape of gas pressure in the cylinder, arcuate valves between and slideable lengthwise of said outer cylinder on the one hand and said inner cylinder and sealing-ring on the other hand, and means to reciprocate said valves.

der on the one hand and said inner cylinder and sealing-ring on the other hand, and means to reciprocate said valves.

5. In an internal-combustion engine, the combination of an outer ported cylinder, a head for said cylinder, a ported expansible sealing-ring in said cylinder, an inner cylinder inside of and spaced inwardly away from said outer cylinder, valve-means between and slidable lengthwise of said outer cylinder on the one hand and said inner cylinder and sealing-ring on the other hand, means to reciprocate said valve-means, means to seal the joints between said inner cylinder, sealing-ring and cylinder-head against gas pressure leakage thereat, a piston slid- 10 able in said inner cylinder, a crank-shaft, a connecting-rod joining said piston and crank-shaft, and means supporting said inner cylinder at its lower end and from which said inner cylinder is demountable upwardly, permitting such inner cylinder to be removed from the upper end of said outer cylinder after removal of said cylinder-head and seal- 15 ing-ring.

6. In an internal-combustion engine, the combination of an outer ported cylinder, a crank-case, a head for said cylinder, a ported expansible sealing-ring in said cylinder, an inner cylinder inside of and spaced inwardly away from said outer cylinder, valve-means between and slidable lengthwise of said outer cylinder on the one hand and said inner cylinder and sealing-ring on the other hand, means to reciprocate said valve-means, means to seal the joints between said inner cylinder, sealing-ring and cylinder-head against gas pressure leakage thereat, a piston slidable in said inner cylinder, a crank-shaft in said crank-case, a connecting-rod joining said piston and crank-shaft, and a support near the lower end of said outer cylinder demountable downwardly while the cylinder-block and upper section of the crank-case remain united and while the crank-shaft remains in place, said inner cylinder being carried by said support and demountable therefrom upwardly, permitting such inner cylinder to be removed from the upper end of said outer cylinder after removal of said cylinder-head and sealing-ring.

7. In an internal-combustion engine the combination of an outer ported cylinder, a crank-case, a head for said cylinder, a ported expansible sealing-ring in said cylinder, an inner cylinder inside of and spaced inwardly away from said outer cylinder, valve-means between and slidable lengthwise of said outer cylinder on the one hand and said inner cylinder and sealing-ring on the other hand, means to reciprocate said valve-means and having detachable connection therewith, a piston slidable in said inner cylinder, a crank-shaft in said crank-case, a connecting-rod joining said piston and crank-shaft, a sup-

port near the lower end of said outer cylinder demountable downwardly while the cylinder-block and upper section of the crank-case remain united and while the crank-shaft remains in place, said inner cylinder being carried by said support and demountable therefrom upwardly, permitting such inner cylinder to be removed from the upper end of said outer cylinder after removal of said cylinder-head and sealing-ring and permitting said valve-means to be removed from the cylinder downwardly, and spring means yieldingly supporting said support, thereby pressing said inner cylinder against said sealing-ring and said sealing-ring against said cylinder-head to prevent gas pressure leak- 80 age at the joints between said inner cylinder, sealing-ring and cylinder-head.

8. In an internal-combustion engine, the combination of an outer ported cylinder, a crank-case, a head for said cylinder, a ported expansible sealing-ring in said cylinder, an inner cylinder inside of and spaced inwardly away from said outer cylinder, valve-means between and slidable lengthwise of said outer cylinder on the one hand and said inner cylinder and sealing-ring on the other hand, an eccentric shaft, an operating rod connecting said eccentric shaft and a lug on said valve-means, said eccentric shaft being chambered 95 to permit said lug to pass thereby when said rod is disconnected from said valve-means, a piston slidable in said inner cylinder, a crank-shaft in said crank-case, a connecting-rod joining said piston and crank-shaft, a support near the lower end of said outer cylinder demountable downwardly while the cylinder-block and upper section of the crank-case remain united and while the crank-shaft remains in place, said inner cylinder being carried by said support and removable therefrom upwardly, permitting such inner cylinder to be removed from the upper end of said outer cylinder after removal of said cylinder-head and sealing-ring, and permitting said valve-means to be removed downwardly after said inner cylinder and support have been de- 105 mounted.

9. In an internal-combustion engine, the combination of an outer ported cylinder, a crank-case, a head for said cylinder, a ported expansible sealing-ring in said cylinder, an inner cylinder inside of and spaced inwardly away from said outer cylinder, arcuate valves between and slidable lengthwise of said outer cylinder on the one hand and said inner cylinder and sealing-ring on the other hand, means to reciprocate said valves and having detachable connection therewith, means to seal the joints between said inner cylinder, sealing-ring and cylinder-head against gas pressure leakage thereat, a piston slidable in said inner cylinder, a crank-shaft in said crank-case, a connecting-rod joining said piston and crank-shaft, a support near the lower 115 120 125 130

- end of said outer cylinder demountable downwardly while the cylinder-block and upper section of the crank-case remain united and while the crank-shaft remains in place, said inner cylinder being carried by said support and removable therefrom upwardly, permitting such inner cylinder to be removed from the upper end of said outer cylinder after removal of said cylinder-head and sealing-ring, the upper end of one of said valves 10 and the lower end of the other of said valves being cut away to facilitate their downward removal from the outer cylinder after said inner cylinder and said support have been removed.
- 15 10. In an internal-combustion engine, the combination of an outer ported cylinder, a head for said cylinder, an inner cylinder inside of and spaced inwardly away from said outer cylinder, a ported expansible sealing- 20 ring between said inner cylinder and said cylinder-head, valves between and slideable lengthwise of said outer cylinder on the one hand and said inner cylinder and sealing-ring on the other hand, means to reciprocate 25 said valves, means to seal the joints between said inner cylinder, sealing-ring and cylinder-head against gas pressure leakage thereat, a piston slideable in said inner cylinder, a 30 shaft, means operatively connecting said piston and shaft, and means to support said inner cylinder from near its lower end only and from which said cylinder is detachable, said inner cylinder being of such size that when 35 detached from said supporting means it may be removed upwardly from said outer cylinder, said cylinder-head and sealing-ring having been first removed.

In witness whereof I have hereunto set my
hand.

RALPH L. SKINNER.
